LUBRICATING SYSTEM FOR ROCK DRILLS

Otto J. Schorer, Holyoke, Mass., assignor to
Worthington Pump and Machinery Corporation,
Harrison, N. J., a corporation of Delaware

Application July 31, 1945, Serial No. 607,941

3 Claims. (Cl. 184—55)

1

This invention relates to percussive tools and more particularly to an oiling or lubricating structure for pressure fluid actuated rock drills.

An object of the present invention is to provide a lubricating system for rock drills or the like, which will supply the necessary lubricating oil to the various working parts of the drill, utilizing the back pressure of the operating pressure fluid to distribute oil to certain of the surfaces requiring lubrication and utilizing the direct action of the pressure fluid to lubricate other parts of the drill, so as to insure proper and sufficient lubrication of all wearing parts of the drill.

With these and other objects in view as may appear from the accompanying specification, the invention consists of various features of construction and combination of parts, which will be first described in connection with the accompanying drawing showing a longitudinal section through a rock drill constructed in accordance with the invention, and the features forming the invention will be specifically pointed out in the claims.

Referring more particularly to the drawing, the rock drill of the hammer piston type may be of any approved form and comprises the cylinder 1 in which the piston 2 is reciprocated by means of air or other suitable fluid under pressure.

The pressure fluid enters the rock drill through the throttle valve 3 and passes into the annular distributing channel 4 from where it passes through suitable ports and passages under control of the control valve 5 into the cylinder 1 for reciprocating the piston 2 in the usual manner of operation of rock drills and other percussive tools of this type. A lubricant chamber 6 is formed in the wall of the cylinder 1 and has a filling opening in one end which is normally closed by the plug 7. An orifice plate 8 is located in the reservoir 6 a suitable distance inwardly from the inner end of the plug 7 and has a restricting orifice 9 therein. The space between the orifice plate 8 and the inner end of the plug 7 is filled with felt or other absorbent material.

An opening or passageway 10 establishes communication between the felt-containing chamber 11, which is the space in the reservoir 6 between the orifice plate 8 and the plug 7, and the passage 12 formed in the cylinder 1. The passage 12 has communication with the annular distributing channel 4 and with the chamber in which the control valve 5 operates.

The cylinder front head 13 has an annular oil chamber 14 formed therein, and this chamber

2

14 has communication through an opening 15 with the oil reservoir 6. One or more grooves 17 are cut in the perimeter of the flange 18 formed on the rear end of the cylinder front head 13, and it or they establish communication passages through which lubricant may pass from the chamber 14 into the cylinder 1 forwardly of the head 19 of the piston 2.

In operation, pressure air is admitted, when 10 the throttle valve 3 is open, into the channel 4, and passes through the passageways 12 and 10 into the felt-containing chamber 11, and through the orifice 9, chamber 6, and opening 15 into the oil chamber 14. This pressure air forces a small 15 amount of oil in vapor form through the groove or grooves 17 into the cylinder where it contacts the surfaces of the reciprocating piston 2. This flow of oil or lubricant takes place during the return or rearward movement of the piston 2. 20 Some of the oil or lubricant which is distributed to the piston 2 through the groove or grooves 17 passes forwardly along the piston 2 during successive operation, and works its way into the chuck structure 20 to provide proper lubrication thereof.

When the piston is making its forward stroke, 25 and as it approaches its cushioning position, as shown in the drawing, it builds up a pressure forwardly of the piston head 19 in excess of the pressure through the passages 10 and 4 (owing to 30 a pressure drop caused in these passages by the action of the valve 5) and pressure air together with oil vapor is forced through the opening 15 into the chamber 6 through the orifice 9, felt chamber 11, passages 10 and 12 into the chamber 35 in which the valve 5 operates, thus lubricating the valve. At this time oil vapor is also carried or forced into the cylinder 1 rearwardly of the piston head 19 where the oil vapor lubricates the cylinder walls, the rifle bar 21 and all other 40 moving parts of the drill in the rearward part thereof.

It will be understood that the invention is not to be limited to the specific construction or arrangement of parts shown, but that these may 45 be widely modified within the invention as defined by the claims.

What is claimed is:

1. In a lubricating device for rock drill the combination of a cylinder, a piston reciprocable 50 therein and having a head, a valve chamber in the rear end of said cylinder, a front head for the cylinder, said cylinder provided with ports and passages for the distribution of pressure air, said cylinder provided with an oil chamber, said front head having an oil chamber therein, a pas-

sage in the cylinder establishing communication between the oil chamber in the cylinder and the oil chamber in said front head, said front head having a passageway cut therein opening from its contained oil chamber into the cylinder in front of the forward end of the piston head, and said cylinder having a passageway therein establishing communication between the cylinder contained oil chamber and one of said cylinder contained pressure air passageways.

2. In a lubricating device for rock drills the combination of a cylinder, a piston reciprocable therein and having a head, a valve chamber in the rear end of said cylinder, a front head for the cylinder, said cylinder provided with ports and passages for the distribution of pressure air, said cylinder provided with an oil chamber, said front head having an oil chamber therein, a passage in the cylinder establishing communication between the oil chamber in the cylinder and the oil chamber in said front head, said front head having a passageway cut therein opening from its contained oil chamber into the cylinder in front of the forward end of the piston head, and said cylinder having a passageway therein establishing communication between the cylinder contained oil chamber and one of said cylinder contained pressure air passageways, and an orifice plate having a restricting orifice therein in said cylinder contained oil chamber.

30

3. In a lubricating device for rock drills the combination of a cylinder, a piston reciprocable therein and having a head, a valve chamber in the rear end of said cylinder, a front head for the cylinder, said cylinder provided with ports and passages for the distribution of pressure air, said cylinder provided with an oil chamber, said front head having an oil chamber therein, a passage in the cylinder establishing communication between the oil chamber in the cylinder and the oil chamber in said front head, said front head having a passageway cut therein opening from its contained oil chamber into the cylinder in front of the forward end of the piston head, and said cylinder having a passageway therein establishing communication between the cylinder contained oil chamber and one of said cylinder contained pressure air passageways, and an orifice plate having a restricting orifice therein in said cylinder contained oil chamber, said orifice plate forming a chamber in one end of the oil chamber, absorbent material in said chamber formed by said orifice plate, said passageway which establishes communication between said cylinder contained oil chamber and one of said cylinder contained air passageways opening into the chamber formed by said orifice plate.

OTTO J. SCHORER.
